John Brandon Williams Jr. Esq.
Sellers Palace Apr.

Apr. 18, 18-

The Schedule referred to in the Sellew Patent were making part of the same
containing a description in the words of, he said, John Brandon himself,
of his improvement in the Portable Horn-powder.

87, all whom it may concern; Be it known that I John
Branson of Williamsport in the County of Lycoming in the State of Penn-
sylvania have invented certain improvements in the portable horse
piano and will hereby declare that the following is a full and exact
description thereof. To sustain the shaft & wheel carry the wheels I
make a frame of wood consisting of two stout planks one of which is to stand
in the ground, or on any convenient foundation, they may be each about
five feet long one foot wide and four inches thick. The other to be raised
to about the height above it, say one foot six inches for which purpose
there are two end pieces into which the before named planks are
joined round headed, asty screws, bolts or otherwise; the bottom plank
contains the steps in which the lower ends of the shafts are to stand and
in the upper plank there are to be boxes to sustain the upper ends; the
wheel pinions and other parts employed may vary in their dimensions
in describing them however it will be convenient to designate certain
sized but still I wish it to be distinctly understood that I do not intend to
confine myself in these particulars nor indeed to the exact
mode of gearing designated by me. The diameter of the main driving
wheel may be about six feet, this stands on the upper side of the piano
diametrical 100 or 110 inches upon the vertical shaft of which there are
two; the upper end of this first shaft passes through the top plank and
there is a hole in the lower side of the driving wheel at its center
about which fits on the end of the shaft to the upper side of this
driving wheel the two or three to which the horse is geared, is to

be fastened by any suitable contrivance. In driving wheel gears, a pinion on the upper end of the second shaft, to which pinion may be about eight inches in diameter. Upon this second shaft there is to be a second driving wheel which may be of the same diameter with the first in, to which case it will mesh into a pinion on the first named shaft of the same size with that on the second shaft. Upon the first shaft below the pinion there is a back wheel hub. It may be of the same size with the driving wheel, this gear is a back pinion upon a horizontal shaft running in suitable bearings below it. This pinion may be of the size of the other pinions but is vary according to the speed with which it is required that the horizontal shaft shall revolve. The ratio and of the horizontal may carry a wheel to receive a strap or band to be connected with another convenient way with the machinery to be driven. All the wheels and pinions may be of cast iron and the shafts of case wrought for the purpose of perfect adjustment so that the teeth may be made to mesh into each other correctly and that the degree in which they do so may be regulated. I adopt regulating keys or wedges to the step boxes of the shafts and also to the boxes in the upper plank in which the upper ends of the shafts run. For the purpose of adjusting the step boxes a mortice is made through the lower plank from side to side immediately under each shaft and into these a wedge shaped key is fitted by driving this key one may, after the step, which rests upon it is moved or turned. The upper of the shafts run in divided boxes to each of which there is a key fitted in like manner. Mortices running through the upper plank made by means of these the shafts may be moved nearer together or further apart, and the mesh of the teeth nicely adjusted.

The divided boxes in which the first shaft runs, rise above the upper plank to as to form a bearing upon which the hub of the driving wheel rests, and by this means it is prevented from pressing upon the shaft or wheel below. I avoid the first driving wheel's pinion in which it gears, may be below the plate, suitable arrangements

6146X

being unable to extract the shafts or bars to a such or collar extract
up through the plate, or to make the upper plank in two pieces joined by
such as to much in the center of the shaft as by this means the shaft
may be removed without the necessity of disturbing the wheels and
spokes fixed upon them. The two holes of the plank are to be secured
together by some bolts.

I also claim as my invention is the general mode or
plan for supporting the shafts and gears in a portable horse
power by means of keys, operating as herein before set forth.
I also claim the adapting of the key in which the first shaft runs
to the supporting of the right of the first driving wheel, as above
described.
